UNITED STATES PATENT OFFICE.

ELMER R. COE, OF WILKINSBURG, AND ROBERT M. GILSON, OF PITTSBURGH, PENNSYLVANIA, ASSIGNORS TO THE UNION SWITCH & SIGNAL COMPANY, OF SWISSVALE, PENNSYLVANIA, A CORPORATION OF PENNSYLVANIA.

RAILWAY SIGNALING.

1,310,608.

Specification of Letters Patent. Patented July 22, 1919.

Application filed August 7, 1916. Serial No. 113,438.

To all whom it may concern:

Be it known that we, ELMER R. COE and ROBERT M. GILSON, citizens of the United States, residing at Wilkinsburg and Pittsburgh, respectively, in the county of Allegheny and State of Pennsylvania, have invented certain new and useful Improvements in Railway Signaling, of which the following is a specification.

10 Our invention relates to signaling for electric roads in which the rails carry alternating propulsion current as well as signaling current.

One object of our invention is to provide 15 means for preventing a large part of the propulsion current from entering the windings of the relays. This and other objects of our invention will appear in the following description.

20 We shall describe one form of apparatus embodying our invention and then point out the novel features thereof in claims.

In the accompanying drawings, Figure 1 is a diagrammatic view showing one form 25 and arrangement of apparatus and circuits embodying our invention. Fig. 2 is a diagrammatic view showing the electrical equivalent circuit through which winding W_1 of relay R in Fig. 1 is connected to the 30 track rails. Fig. 3 is a view showing a vector diagram for the signaling current in the track connections of winding W_1 of relay R. Fig. 4 is a view showing for the propulsion current a diagram similar to Fig. 3. Fig. 35 5 is a perspective view showing more in detail the relay R shown in Fig. 1.

Similar reference characters refer to similar parts in each of the several views.

Referring first to Fig. 1, reference characters 40 4 and 5 designate the track rails of a railway, which rails are divided into sections by insulated joints 2, there being shown in the drawing only one section A—B, and the beginning and end respectively of the adjoining sections. For the control of traffic through section A—B we provide a signal S having a semaphore arm 20, which when in the vertical position indicates "proceed" and when in the horizontal position indicates "stop". The positions of the signal semaphore are controlled by a local circuit, comprising a contact c and a source of current 22, this control being such that the semaphore 20 is in the vertical or the hori-

zontal position respectively according as 55 contact c is closed or open. The contact c is operated (as we shall describe fully hereinafter) by a relay R comprising a rotor 23 responsive to currents in windings W_1 and W_2 . Winding W_2 is constantly energized, being directly connected to a transformer P fed from a transmission line N, receiving alternating signaling current from generator H. Winding W_1 receives current from a track circuit which comprises the 60 rails 4 and 5 of section A—B, a source of signaling current, here shown as a transformer M fed from transmission line N, connected to the rails adjacent one end of section A—B, and current responsive apparatus connected to the other end of the section. As here shown, the current responsive apparatus comprises an open core step-up transformer T, the secondary of which is connected in series with a condenser C and 70 winding W_1 , of such relative proportions that this secondary circuit is substantially resonant at the frequency of the signaling current, which for purposes of illustration we shall assume to be 60 cycles. 75

Fig. 2 shows the electrical equivalent circuit for this transformer and its secondary circuit when the ratio of transformation is 1:1, as we shall assume herein for simplicity of the vector diagrams. This equivalent circuit comprises an inductive impedance V in parallel with the condenser C and winding W_1 , the impedance V being inserted in the diagrammatic circuit to account for the magnetizing current taken by the transformer, which current is rather large because 80 of the open core. 85

Referring now to Fig. 3, vector OE represents the signaling current voltage on transformer T, and therefore also the voltage across condenser C and winding W_1 in series. The components of this voltage on the winding and the condenser are shown by vectors OL and LE respectively. Voltage OE causes a flow of current OD through 95 impedance V, which current is equivalent to the magnetizing current of the transformer. Condenser C and winding W_1 being in resonance, take a current OK substantially in phase with voltage OE. Vector OF, the resultant of vectors OD and OK, shows the 100 total current supplied to the transformer. 105

The current in winding W_1 coacts with the

current in winding W_2 to produce rotation of rotor 23 whereby the contact c of the relay is actuated to the closed position, as I shall now describe with reference to Fig. 5. The 5 rotor 23 is mounted on a vertical shaft 26, which terminates at its upper end in arms 27. Bell cranks 61 of a centrifugal governor G are pivotally mounted in the slotted ends of arms 27 by means of pins 62, so that the 10 bell cranks are free to swing in a vertical plane. A fly ball 60 is attached to one arm of each bell crank and causes it to depend vertically from its point of suspension when the rotor is standing still. The end of the 15 other arm of each bell crank is ball-shaped and is inserted in a hole 63 through a sleeve 64 fitting loosely over a rod 28. The lower end of rod 28 is inserted into a vertical hole 67 in shaft 26 and fits loosely therein so that 20 shaft 26 can rotate with respect to the rod. The upper end of rod 28 is bifurcated and pin-connected to an arm 29 riveted to a bracket 30 mounted on pivots 31. The contact c operated by the relay comprises a contact finger 21 fixed to the bracket 30 by 25 means of insulated studs 9, in such manner that the tip of the finger engages a stationary contact point 36. Contact c is normally held open by a weight W mounted on an arm 30 40, the extremity of which arm rests on a support 41 when the contact is open. Current in winding W_1 causes the rotor 23 to turn so that the balls of the governor fly apart. By means of the bell cranks 61, sleeve 35 64 is moved downwardly, so that it engages a collar 65 integral with rod 28. The rotor is prevented by suitable means from moving vertically upward; consequently, rod 28 is pulled downward by means of governor G 40 with a force depending upon the speed of rotation of the rotor, which speed depends upon the frequency of the current. The weight W is so adjusted that its biasing force on bracket 30 is not overcome by the 45 downward force on rod 28 until the rotor has accelerated to a speed corresponding to the frequency of the signaling current, namely, 60 cycles. When, therefore, the signaling current energizes winding W_1 , the relay contact c closes the circuit of signal S, which 50 signal therefore gives the proceed indication.

Referring again to Fig. 1, when a vehicle V enters section A—B, its wheels and axles form a path of low resistance from one track rail to the other, so that nearly all of the 55 signaling current is diverted from transformer T. The current in winding W_1 is negligibly small and unable to continue to rotate rotor 23. The governor fly balls are 60 therefore unable to hold contact c closed against the action of weight W, so that the circuit for signal S is broken and the semaphore 20 drops to the stop position. Thus it appears that due to the flow of signaling 65 current in the track circuit, the relay R

causes signal S to indicate "proceed" or "stop" according to whether or not there is a train in section A—B.

Propulsion current for the operation of cars or trains along the railway is furnished 70 by an alternator G, one terminal of which is connected to a trolley wire or third rail L, and the other terminal of which is grounded to the track rails. The propulsion current has a lower frequency than the signaling current, generally 25 cycles, which value 75 we shall assume for present purposes. This propulsion current flows from one terminal of the generator through wire L, vehicle V, track rails 4 and 5 in parallel to the other 80 terminal of the generator G. Impedance bonds I are provided for passing the propulsion current around the insulated joints without interfering with the flow of the 85 signaling current as well understood in the art. In flowing through the vehicle the current drives the propulsion motors which we have not shown on the drawing.

For a variety of causes, to mention only unequal bonding combined with unequal 90 grounding of the track rails, it may happen that for the propulsion current the voltage of one track rail in section A—B is higher than the voltage of the other rail, so that a part of the propulsion current flows from 95 one track rail to the other through the transformer T.

If the propulsion current in transformer T should enter winding W_1 of relay R, in 100 excessive amount, it would cause a saturation of the stator core and retard the speed of rotor 23 so that contact c would open and signal S would indicate "stop", even though there were no train in section A—B. By our invention the portion of the propulsion current that actually reaches winding W_1 is reduced to a small fraction of the current entering transformer T from the track rails. This is shown by the vector 105 diagram Fig. 4, wherein $O'K'$ is a vector representing the propulsion current in winding W_1 , assumed for present purposes equal in amount to the signaling current in the relay. The voltage then on relay winding W_1 is vector $O'L'$, smaller than the corresponding vector OL in Fig. 3, because the inductance of the winding decreases with the frequency of the current. The voltage on condenser C is larger than before, as shown by vector $L'E'$, because the reactance of a condenser varies inversely as the frequency. The voltage on the transformer, or the voltage 120 on coil V in the electrical equivalent diagram Fig. 2, is the vector sum of the above two voltages, i. e., vector $O'E'$. The magnetizing current of the transformer or the current through impedance V of Fig. 2, is represented by vector $O'D'$, larger than the corresponding vector OD of Fig. 3, because the voltage on the transformer is higher and 125 130

the voltage on the transformer is higher and 130

because the magnetizing current of a transformer increases with decrease of frequency. The total propulsion current, then, supplied to the transformer is shown by vector $O'F'$, the sum of the magnetizing current $O'D'$ and the current $O'K'$ in the relay winding. By comparing the vector $O'F'$ with the corresponding vector OF in Fig. 3, it is apparent that for the same amount of current in winding W_1 , a far greater propulsion current must flow into the transformer than signaling current. It appears, therefore, that the possible effect of the propulsion current on the relay is considerably lower when the relay is connected to the rails in accordance with our invention than when the relay is directly connected to the rails, as usual in present practice, whereas at the same time the signaling current is practically unaffected in its operation of the relay. Thus considerable propulsion current may flow into transformer T before enough of this current enters the relay to open contact c .

If it happens that propulsion current enters both windings W_1 and W_2 , this current produces rotation of rotor 23 even when the signaling current is not present in winding W_1 . Due to the lower frequency, however, the speed of rotation is not as high as required for the operation of the relay contact c by the centrifugal governor, as well understood in the art, and the propulsion current can therefore under no circumstances cause a false closure of contact c and a false proceed indication of signal S .

Although we have herein shown and described only one form of apparatus embodying our invention, it is understood that various changes and modifications may be made therein within the scope of the appended claims, without departing from the spirit and scope of our invention.

Having thus described our invention, what we claim is:

1. In combination, a relay comprising an energizing winding, a transformer having an open magnetic circuit, and a secondary circuit for said transformer including said relay winding, whereby when the primary of said transformer is supplied with equal alternating currents differing in frequency said relay winding receives considerably more current of the higher frequency than of the lower frequency.

2. In combination, a relay comprising an induction motor having two windings, a contact, speed responsive means for governing said contact by said motor, means for supplying current to one winding, means for supplying current to the other winding, said latter means comprising an open core transformer, having a magnetizing current increasing with decrease of frequency, a condenser and said last-mentioned relay

winding connected in the secondary circuit of said transformer, said circuit being resonant at a predetermined frequency, so that when said transformer is supplied with current of said predetermined frequency and also with current of a lower frequency, said winding is energized by a proportionately greater amount of the former current than of the latter current.

3. In combination, a relay comprising an induction motor having two windings, a contact, speed responsive means for governing said contact by said motor, means for supplying current to one winding, means for supplying current to the other winding, said latter means comprising a transformer, a condenser and said last-mentioned relay winding connected in the secondary circuit of said transformer, said circuit being resonant at a predetermined frequency and said transformer having an open core so that it has a high magnetizing current at a lower frequency than said predetermined frequency, so that when said transformer is energized by currents of said frequencies, said winding is energized proportionately more by one current than by the other.

4. In combination, a relay comprising an induction motor having two windings, a contact, speed responsive means for governing said contact by said motor, means for supplying current to one winding, means for supplying current to the other winding, said latter means comprising an open core transformer, and a secondary circuit therefor comprising a condenser and said last-mentioned relay winding, said circuit being resonant at a predetermined frequency.

5. In combination, a relay comprising an energizing winding, a transformer having an open magnetic circuit; a circuit including in series the secondary winding of said transformer, the said relay winding and a condenser; said circuit being resonant at a predetermined frequency, whereby when the primary of said transformer is supplied with current at said predetermined frequency and also with an equal current at a lower frequency, said relay winding receives considerably more current at the predetermined frequency than at the lower frequency.

6. In combination, a relay comprising an induction motor having two windings, a contact, speed responsive means operated by said motor for controlling said contact, an open core transformer, a secondary circuit therefor comprising in series a condenser and one of said motor windings, said circuit being resonant at a predetermined frequency, and means for supplying a plurality of currents differing in frequency to the primary of said transformer.

7. In combination, a relay comprising an induction motor having two stator windings, a contact, speed responsive means op-

erated by said motor for actuating said contact when current of a predetermined frequency is supplied to both of said motor windings, a transformer having an open 5 magnetic circuit, and a secondary circuit for said transformer including one of said relay windings, whereby when the primary of said transformer is supplied with current of said predetermined frequency and also 10 with an equal current of a lower frequency, the relay winding which is sup-

plied by the secondary of the transformer receives considerably more current of the predetermined frequency than of the lower frequency.
